SWAB.

Application filed January 17, 1927. Serial No. 161,694.

This invention is a swab for removing paraffin and heavy oils from a well casing; and it is an object of the invention to combine a usual swabbing medium and a cutting means which is adapted to positively cut heavy hydrocarbons from the wall of a well casing, the paraffin and the like which is thus dislodged passing into a hollow bore extending through the device, where it is trapped against back-flow during subsequent withdrawal of the swab, so that the tight engagement of the swabbing medium with the casing wall removes all of the dislodged material from the well.

It is a further object of the invention to provide a cutting means above and below the swabbing medium so as to positively cut away heavy hydrocarbons as the swab is either raised or lowered, and to arrange the cutting means so as to present a maximum cutting surface and automatically clear away the dislodged material without clogging.

It is a still further object of the invention to provide a valvular means automatically opening as the swab is lowered to permit passage of the dislodged material into a hollow bore of the device, and automatically closing as the swab is withdrawn in order to prevent back-flow of the dislodged material.

It is a still further object of the invention to provide for escape of fluid as the swab is lowered in a well, so that pressure in the well will not retard said lowering movement, and to automatically shut-off said escape of fluid when the swab is withdrawn, the said automatic shut-off means being positioned above the cutting elements of the device where it will not hinder ready replacement of the cutters when they become worn.

It is a still further object of the invention to arrange the swabbing medium which is positioned between the end cutters, so as to maintain a fluid tight engagement with the wall of the well casing without subjecting the swabbing medium to excessive wear.

It is a still further object of the invention to arrange the swabbing medium so as to form a vacuum contact adapted to maintain a fluid tight engagement and cool the swab for preventing its burning when it is not submerged in fluid, the arrangement of the

swabbing medium also providing for collection of sand and cuttings so that such foreign matter will not score or cut the swab.

Further objects of the invention will be readily understood from the following description of the accompanying drawings, in which:

Fig. 1 is a side elevation, partly in axial section, showing the swab in operation in a well with the device divided and its upper and lower ends shown alongside one another.

Figs. 2 and 3 are transverse sections on the lines 2—2 and 3—3 of Fig. 1.

The swab is suspended from a usual string of cable tools 1 in the casing 2 of a well, a coupling 3 being provided at the upper end of the swab for engagement by a usual pin 4 on the end of the cable tools.

The coupling collar 3 is provided with a hollow coupling 5 depending therefrom, and an open ended pipe 6 on which the swabbing elements are mounted is threaded into the coupling 5. Above the open end of pipe 6 the bore of coupling 5 is threaded to receive a valve seat 7, and an upwardly opening gravity valve 8 cooperates with the valve seat, to open or close the bore of pipe 6 to the upper portion of the hollow coupling 5, which is slotted as shown at 9 for open communication with the bore of the well casing.

Pipe 6 supports upper and lower cutting means and an intermediate element forming a tight packing engagement with the wall of casing 2, the said intermediate element having a hollow bore and adapted for limited sliding movement of pipe 6 relative thereto to open or close its hollow bore.

The upper cutter for the swab may be mounted on pipe 6 immediately below coupling 5, with the lower cutter preferably mounted on the extreme lower end of the pipe; and each cutter is illustrated as comprising a sleeve 10 on pipe 6, with axially spaced collars 11—12 mounted on said sleeve and connected by outwardly bowed spiral springs forming cutting blades 13.

The ends of the springs are equidistantly, circumferentially spaced, and may be fixed by pins 14 to rings 15; and the rings are illustrated as mounted in annular counterbores in the proximate ends of collars 16 which are threaded onto collars 11—12, so

that the rings are held in place by abutment against shoulders 17 at the proximate ends of collars 11-12.

The sleeve 10 is fixed relative to pipe 6, and collar 12 at the lower end of the cutter is preferably fixed relative to the sleeve, as for example by common fastening means shown as rivets 18; and the collar 11 at the upper end of the cutter is adjustable along sleeve 10 to adjust the diameter of the bowed cutter formed by spring blades 13.

As an instance of this adjustment, a threaded connection 19 is provided between sleeve 10 and collar 11, and the shouldered inner end 17 of the collar forms a nut 17^a for turning the collar. The collar may be locked in threaded adjusted position by a set screw 20 which may also extend through collar 16 for locking it on collar 11; and the collar 16 on the lower collar 12 may be locked in place by a set screw 21.

The respective cutters at the ends of the swab function as the device is raised and lowered in a well, in order to dislodge paraffin and heavy oils from the wall of the well casing by the cutting engagement of the edges of spiral blades 13, and the blades of the respective cutters spiral in opposite directions so that each cutter will have maximum cutting efficiency when the swab is moved in the direction to cause it to function. The spiral disposition of the blades provides a maximum cutting surface, and in conjunction with the hollow construction formed by the bowed arrangement of the blades, affords a positive means for removing the dislodged material from the blades and passing it beyond the cutters.

The swab proper which is mounted on pipe 6 between the upper and lower cutter, functions immediately after the cutting action produced by raising or lowering the device, in order to complete the removal of heavy oils and the like from the wall of the well casing; and this swabbing element has a hollow bore adapted to open for reception of the dislodged material as the device is being lowered in a well, but adapted to automatically close when the swab is withdrawn, so that all of the dislodged material is removed from the well.

As an instance of this arrangement a sleeve 25 is slidable on pipe 6 between the cutters, and the sleeve is spaced from the pipe to form a hollow bore, by means of a guide nut 26 threaded on the upper end of the sleeve and slidably engaging the pipe. The nut 26 has bores 27 in alignment with the hollow bore of sleeve 25 to permit unobstructed flow of fluid; and the lower end of the upper cutter of the device is adapted for abutment against the nut 26 to limit downward movement of pipe 6 relative to sleeve 25.

The lower end of sleeve 25 has a valve seat

29 threaded thereon, which cooperates with a valve 30 fixed on pipe 6 in order to open or close the hollow bore of the sleeve when the pipe is lowered or raised relative to the sleeve. The valve 30 preferably has a guide head 31 extending into sleeve 25 for maintaining alignment of the parts, and the guide head has axial bores 32 for unobstructed flow through the hollow bore of the sleeve.

Swab rubbers 33, preferably two in number, are mounted on sleeve 25 and may have their proximate ends spaced by a ring 34, with their respective distant ends abutting against the supporting annulus of valve seat 29 and against an adjusting nut 35 which is threaded on sleeve 25 below guide nut 26. The ends of the swab rubbers are preferably formed with axially projecting reduced collars adapted for reception in cooperating grooves 36 in the abutting ends of nut 35, ring 34 and the supporting annulus of valve seat 29, in order to secure the swab rubbers in place; and the rubbers in addition to the radial expansion obtained by tightening nut 35, are preferably subjected to fluid pressure 90 for maintaining a tight engagement with the wall of casing 2.

For this purpose slots 38 open through sleeve 25 in back of the swab rubbers, so that pressure in the hollow bore of the sleeve 95 tends to radially expand the rubbers; and in order to maintain a fluid tight connection between the swab rubbers and the casing wall without subjecting the rubbers to undue wear, annular grooves 39 may be provided in 100 the contact faces of the rubbers, said grooves forming vacuum recesses when the swab is in use, which tend to maintain a tight engagement between the rubbers and the casing wall.

The grooves 39 further tend to prolong the life of the swab rubbers by providing an air cooling effect for preventing burning of the swab when the latter is not submerged in fluid; and the grooves will also collect 110 sand and cuttings and thus prevent such foreign matter from scoring or cutting the swab rubbers by passing along the same from end to end. The recessed construction of the swab rubbers thus prolongs their 115 life and also increases their swabbing efficiency.

In operation, the device is lowered in casing 2, the valve 8 readily opening to relieve pressure in the well through the hollow 120 pipe 6, and the swab rubbers engaging the casing wall so that pipe 6 is lowered relative to sleeve 25 for opening valve 30. The open bore of pipe 6 together with the open valve 30 thus prevents a discharge passageway for dislodged material and for pressure in the well which is substantially equal to the cross-sectional area of the swabbing medium, and the swab may thus be readily lowered in the well irrespective of 130

the pressure which is encountered. The lower cutter functions during downward movement of the device, for cutting paraffin and heavy oils from the casing wall, and the dislodged material is held against dropping by the spiral blades and is thus directed past open valve 30 into the hollow bore of sleeve 25. The swab rubbers engaging the casing wall in back of the lower cutter, completes the removal of the heavy oils.

When the device is subsequently withdrawn from the well, the swab rubbers tend to stick in the casing, so that valve 30 is immediately closed by elevation of pipe 6 relative to sleeve 25, and valve 8 is closed by the pressure above the swab. As a consequence, the dislodged heavy oils above the swab or in the hollow bore of sleeve 25, are trapped against back-flow, and during elevation of the device the upper cutter first dislodges any remaining heavy oils on the wall of the well casing, and the fluid tight engagement of the swab rubbers then withdraws all of said heavy oils from the casing. In the event of the swab sticking during its withdrawal so that it is necessary to unload the dislodged material which has been trapped, pipe 6 is lowered relative to the sleeve 25 which will again be held against axial displacement by the swabbing rubbers engaging the casing wall, and the valve 30 is thus opened for unloading the dislodged material from the sleeve 25.

We claim:

35. 1. A device of the character described comprising a medium adapted for swabbing engagement with the wall of a well casing and having an open bore, means axially beyond said swabbing means adapted for cutting engagement to dislodge paraffin and heavy oils from the casing wall, and a valve for the open bore of the swabbing medium between the swabbing medium and the cutting means.

40. 2. A device of the character described comprising a medium adapted for swabbing engagement with the wall of a well casing and having an open bore, means axially beyond each end of the swabbing medium adapted for cutting engagement to dislodge paraffin and heavy oils from the casing wall as the device is raised and lowered in the casing, and a valve for the open bore of the swabbing medium between the swabbing medium and the lower cutting means.

45. 3. A device of the character described having means at its lower end adapted for cutting engagement to dislodge paraffin and heavy oils from the wall of a well casing, and positively actuated valvular means above the cutting means adapted for downward movement of the device past the dislodged material and preventing back-flow of the dislodged material as the device is withdrawn from the casing.

4. A device of the character described comprising means adapted for cutting engagement to dislodge paraffin and heavy oils from the wall of a well casing, a medium above said cutting means adapted for swabbing engagement with the wall of the well casing, said swabbing means having an open bore, and positively actuated valvular means for said open bore between the swabbing medium and the cutting means, said valvular means being adapted to be opened for reception of the dislodged material after the device is lowered in the casing and adapted to be closed to prevent back-flow of the discharged material as the device is withdrawn from the casing.

5. A device of the character described having a bore and including spirally disposed means adapted for cutting engagement to dislodge paraffin and heavy oils from the wall of the well casing and positively support said dislodged material for lowering of the device past said discharged material so that said material enters the bore of the device, and means for preventing back-flow of the dislodged material through said bore during withdrawal of the device from the casing.

6. A device of the character described comprising means adapted for cutting engagement to dislodge paraffin and heavy oils from the wall of a well casing, said cutting means comprising axially spaced collars having exterior shoulders at their proximate ends, rings mounted on said collars and abutting axially against said shoulders, a plurality of spirally disposed, outwardly bowed, spring cutter blades fixed at their respective ends to the respective rings, and counter-bored collars received over the ends of said springs and fixed to the shouldered collars.

7. A device of the character described comprising means adapted for cutting engagement to dislodge paraffin and heavy oils from the wall of a well casing, and means for adjusting said cutting means for operative engagement with the wall of the casing, said adjusting means comprising a threaded connection and a retaining means for locking said threaded connection in adjusted position.

8. A device of the character described having a bore and a normally closed valve for said bore adapted to open upon lowering of the device in a well casing, and means below said valve adapted for engagement with the wall of the casing for dislodging paraffin and heavy oils so that said material is supported by the dislodging means in order that it may enter the bore of the device past said open valve.

9. A device of the character described comprising a pipe adapted for suspension from a string of drill pipe, a normally closed valve for the upper end of the pipe adapted to open during lowering of the device in a

well casing, means axially spaced on said pipe below said valve adapted respectively for cutting engagement to dislodge paraffin and heavy oils from the wall of the well casing during lowering and raising of the device in the well casing, a medium adapted for swabbing engagement with the wall of the well casing mounted on said pipe between said cutting means, said swabbing medium having a hollow bore, and valvular means for the hollow bore of the swabbing medium, said valvular means being positioned between the swabbing medium and the lower cutting means and adapted to open during lowering of the device in the well casing for reception of dislodged material in said hollow bore, said valvular means being adapted to close during withdrawal of the device from the well casing to prevent back-flow from said hollow bore.

10. A device of the character described comprising means adapted for cutting engagement to dislodge material from the wall of a well casing, said cutting means comprising axially spaced collars having exterior shoulders at their proximate ends, rings mounted on said collars and abutting axially against said shoulders, a plurality of blades fixed at their respective ends to the respective rings, and counter-bored collars received over the ends of said blades and fixed to the shouldered collars.

11. A device of the character described comprising a medium adapted for swabbing engagement with the wall of a well casing, said swabbing medium having a hollow bore, valvular means for the lower end of the hollow bore, and a valve stem for said valvular means slidable in said hollow bore and adapted for suspension from a drill string, the swabbing medium being adapted for frictional engagement with the wall of the well casing for movement of the valve stem relative thereto so that lowering the device in the well casing will open the valvular means for reception of dislodged material in said hollow bore and withdrawal of the device from the well casing will close said valvular means to prevent back-flow from said hollow bore.

12. A device of the character described comprising a medium adapted for swabbing engagement with the wall of a well casing,

said swabbing medium having a hollow bore, valvular means for the lower end of the hollow bore, and a valve stem for said valvular means slidable in said hollow bore and adapted for suspension from a drill string, said valve stem having a hollow bore open to the well casing below said valvular means whereby said open bore of the valve stem and the open valvular means present a discharge passageway of substantially the cross-sectional area of the swabbing medium, the swabbing medium being adapted for frictional engagement with the wall of the well casing for movement of the valve stem relative thereto so that lowering the device in the well casing will open the valvular means for reception of dislodged material in said hollow bore and withdrawal of the device from the well casing will close said valvular means to prevent back-flow from said hollow bore.

13. A device of the character described comprising a medium adapted for swabbing engagement with the wall of a well casing, said swabbing medium having a hollow bore, valvular means for the lower end of the hollow bore, a valve stem for said valvular means slidable in said hollow bore and adapted for suspension from a drill string, said valve stem having a hollow bore open to the well casing below said valvular means and adapted for discharge into the well casing above said valvular means whereby said open bore of the valve stem and the open valvular means present a discharge passageway of substantially the cross-sectional area of the swabbing medium, and an upwardly opening check valve in the hollow bore of the valve stem, the swabbing medium being adapted for frictional engagement with the wall of the well casing for movement of the valve stem relative thereto so that lowering the device in the well casing will open the valvular means for reception of dislodged material in said hollow bore and withdrawal of the device from the well casing will close said valvular means to prevent back-flow from said hollow bore.

In testimony whereof we have affixed our signatures to this specification.
